Des. 229,780
Patented Jan. 1, 1974

229,780

OVER-HEAD PROJECTOR OR SIMILAR ARTICLE

Tooru Ishida, Yamato-machi, Japan, assignor to
Kabushiki Kaisha Koparu, Tokyo-to, Japan

Filed Sept. 24, 1971, Ser. No. 183,724

Claims priority, application Japan Apr. 7, 1971

Term of patent 14 years

Int. Cl. D16—01

U.S. Cl. D61—1 L

FIG. 1

FIG. 2

FIG. 3

FIG. 4

FIG. 5

FIG. 1 is a front perspective view of an over-head projector or similar article showing my new design in the erected position;

FIG. 2 is a rear perspective view thereof;

FIG. 3 is a bottom perspective view thereof;

FIG. 4 is a front perspective view of the projector in a folded position;

FIG. 5 is a front perspective view of the projector of FIG. 4 with a carrying case cover in position.

I claim:

The ornamental design for an over-head projector or similar article, substantially as shown and described.
